Primary Examiner — George D. Kirschbaum*Assistant Examiner* — Antoinette Martine Suiter(74) *Attorney, Agent, or Firm* — McGarry Bair PC(57) **CLAIM**

The ornamental design for a surveying instrument accessory as shown and described.

DESCRIPTION

FIG. 1 is a top perspective view of a surveying instrument accessory, showing our new design;

FIG. 2 is a bottom perspective view of the surveying instrument accessory of FIG. 1;

FIG. 3 is a top view thereof;

FIG. 4 is a bottom view thereof;

FIG. 5 is a front side view thereof, with the rear side view being identical thereto; and,

FIG. 6 is a left side view thereof, with the right side view being identical thereto.

Portions of the surveying instrument accessory shown in broken lines form no part of the claimed design.

1 Claim, 6 Drawing Sheets(56)
